United States Patent Office.

WILLIAM G. CREAMER, OF BROOKLYN, NEW YORK.

Letters Patent No. 70,812, dated November 12, 1867.

VENTILATING DEVICE FOR RAILROAD CARS.

The Schedule referred to in these Letters Patent and making part of the same.

TO ALL WHOM IT MAY CONCERN:

Be it known that I, WILLIAM G. CREAMER, of the city of Brooklyn, county of Kings, State of New York, have invented a new and improved Mode of Ventilating Railroad Cars; and I do hereby declare that the following is a full and exact description thereof, reference being had to the accompanying drawings, and to the letters of reference marked thereon.

The nature of my invention consists in making openings in the sides of railroad cars for the admission of air, and inserting in the same ventilator-plates constructed to admit the air and exclude the cinders and rain, and thus insuring a full supply of pure air at all times.

To enable others skilled in the arts to make and use my invention, I will proceed to describe its construction and operation.

I construct my railroad car in the ordinary way, and in the space over the windows I make openings through the side, of any required dimensions, (usually about eight inches square,) and in the openings, and flush with the outside of the car, I put my ventilators, constructed as follows: I take sheets of tin plate and perforate them with openings, as shown by letters A B C D, on plate 1. On the back of the sheets I solder half-round pieces of tin, of tunnel shape, shown at A B C D, plate 2. These plates are secured on the side of the car over the openings, with the smooth side *c*, plate 2, outward.

The advantages of this arrangement are that the side of the car presents a smooth, flush surface, over which the painting and lettering can be arranged without regard to the openings, and at the same time air is freely admitted, and the entrance of rain and cinders effectually excluded. Ventilation is always required in a crowded railroad car, even while it is raining; and where plain openings are used it is necessary to close them in rainy weather. The plain openings are also unsightly in appearance, (especially on railroad cars,) causing breaks or stops in the painting and lettering. The plan I have described obviates this, making a surface very nearly smooth and flush, over which the painting and lettering can be as neatly done as if it were a plain surface. These ventilator-plates may also be made of cast iron or other materials. They are also applicable to the ventilation of carriages, omnibuses, cabins of steam and sailing-ships, &c.

It is easy to see that the plan I have described may be greatly modified within the range of my invention. I do not, therefore, limit myself to the precise form of openings and construction described, but

What I claim as my invention, and desire to secure by Letters Patent, is—

The construction and attachment of ventilating-plates to the sides of railroad cars, to admit air and exclude rain and cinders, and present a flush surface, substantially as specified.
